(57) CLAIM

The ornamental design for a loudspeaker as shown and described.

DESCRIPTION

FIG. 1 is a front perspective view of a loudspeaker showing the new design;

FIG. 2 is a rear perspective view thereof;

FIG. 3 is a front view thereof;

FIG. 4 is a side view thereof

FIG. 5 is an opposite side view thereof;

FIG. 6 is top view thereof;

FIG. 7 is a bottom view thereof; and,

FIG. 8 is rear view thereof.

The broken lines and unshaded areas in the figures illustrate portions of the design that form no part of the claimed design.
